UNITED STATES PATENT OFFICE.

LUCIUS V. WALKLEY, OF PLANTSVILLE, CONNECTICUT, ASSIGNOR TO THE H. D. SMITH & COMPANY, OF PLANTSVILLE, CONNECTICUT, A CORPORATION.

DESIGN FOR AN AUTOMOBILE PRY-BAR.

44,327.

Specification for Design.

Patented July 8, 1913.

Application filed December 13, 1912. Serial No. 736,620. Term of patent 14 years.

To all whom it may concern:

Be it known that I, LUCIUS V. WALKLEY, a citizen of the United States, residing at Plantsville, in the county of Hartford and State of Connecticut, have invented a new, original, and ornamental Design for Automobile Pry-Bars, of which the following is a specification, reference being had to the accompanying drawing, forming part thereof.

Figure 1 is a side elevation of my automobile pry bar, showing my new design.

Fig. 2 is a perspective view of the same. Fig. 3 is a central longitudinal section of the same, certain parts being shown in side elevation. Fig. 4 is an enlarged sectional view on the line *x x* of Fig. 1.

I claim:

The ornamental design for an automobile pry bar, as shown.

LUCIUS V. WALKLEY.
